UNITED STATES PATENT OFFICE

GEORGE EDWARDZ BJÖRKMAN, OF DJURSHOLM, SWEDEN

HAIR WINDING MECHANISM

Application filed April 17, 1931. Serial No. 530,790.

This invention relates to hair waving appliances, being directed specifically to a winding element as applied to electrical or vapor heated hair waving devices.

Up to the present time there have been several types of winders applied whereby a series of strands of hair may be wound uniformly about the central rod member which is inclosed within, carries or has formed as part thereof, a heater element. Such winding devices have been made of metal or phenolic condensation products and have been tubular in shape, such winding devices being provided with tongues or projections adapted to direct the displacement or control the position of the strands of hair as wound upon such central rod member.

One of the inherent difficulties of the use of such winding devices, as are at present known to the art, lies in the fact that they can be only operated for rotation in one direction and hence necessitate and permit only the winding of the hair in one direction, while at the same time because of such construction, are not capable independently of themselves to prevent the displacement or movement of the strands of hair inclosed therein from or in another direction.

It is an object of this invention then, to provide for a winding member essentially tubular in shape and formed of a phenolic condensation product which winding member has a structural formation with provisions therein for permitting the rotation of the same in either direction upon the central rod at the same time for preventing the displacement of the strands of hair in either direction.

Specifically it is an object of this invention to provide for a winder device having essentially a tubular shape wherein there is provided a groove in which a series of hair strands are guided for rotation about a central rod, there being provided a plurality of tongues at opposite sides of the groove and formed integral with the walls defining such groove, such tongues being substantially in parallelism one with respect to another, but so formed as to provide for a limiting or restraining mechanism, or element, for producing a winding of strands of hair about a cen-

tral rod independently of the directional rotation of such winder device.

These and other advantages, capabilities and features of the invention will appear from the subjoined detail description of one specific embodiment therefor, illustrated in the accompanying drawing, in which

Fig. 1 represents a side elevation showing the device in operation for wrapping the hair about the central rod member.

Fig. 2 is a side elevation partially in section showing the structure of the winder.

Fig. 3 is a side elevation in enlarged form showing the winder.

Fig. 4 is a plan view and section taken along lines 4—4 of Fig. 3.

Referring to reference characters in the drawing numeral 10 represents a central rod of the type well known in the hair waving industry which has a head 11 at one end thereof and a heat resisting plate member 12 there adjacent, the head member and the plate member as indicated in Figures 1 and 2 both being formed of a plurality of separable parts not shown or described in detail, which may surround a series of hair strands and allow the same to pass therethrough.

Referring particularly to Figures 2, 3 and 4, the winder device 13 comprises of a molded member formed of a phenolic condensation product or other insulating material and has a guide portion 14 of a diameter substantially similar to the outer diameter of the central rod 10, the said guide portion 14 merging into an enlarged receiving portion 15, the said guide portion 14 being knurled as at 16 and the receiving portion is knurled as at 17.

The receiving portion is molded so as to provide for a substantially V shape notch 18, the end of the face 19 of which has projecting across such notch, a tongue 20 while the face 21 of the other side of the notch extends a distance past the tongue 20 and has formed a flared portion or tongue 22 substantially parallel to tongue 20 in one plane but angularly disposed in a different plane so that the same may be considered to be flaring outwardly, as shown in Figures 3 and 4.

Referring in particular to Figures 1 and 2 the strand of hair is passed within the notch

of the winder device which is guided by the member 14 along the central rod 10 and then the hair wound as shown in Figures 1 and 2 in either direction dependent on which face 5 and tongue of the winder the operator wishes to rely on, it being noted that in Figures 1 and 2 that the face 21 and the tongue 22 are the controlling factors in the directional rotation of the strand of hair.

10 It should be noted that the face 19 and the tongue 20 serve to provide a positive stop to prevent displacement or movement or tendency of reversal of movement in opposite direction to that desired by the operator should 15 face 21 and tongue 22 be used.

No showing has been made of the heating elements or the method of inclosing the device in heaters for imparting a wave to the wound hair strands but it is to be understood 20 that this invention relates specifically to the winding element per se irrespective of the remaining elements associated therewith in the production of a permanent wave.

25 It is obvious that various changes and modifications may be made to the details of construction without departing from the general spirit of the invention as set forth in the appended claims.

I claim:

30 1. A winder element for hair waving devices, comprising a stem, a hollowed member of insulating material, one portion of which has a greater bore than the second, said portion having the smaller bore being adapted to 35 slide along said stem, the portion having the larger bore being adapted to have a groove and a plurality of tongues disposed substantially in parallelism, but extending in directions opposite one to the other, said tongues 40 being respectively adapted to guide hair wound on said stem, as the winder element is rotated in either direction.

2. A winder for use in hair waving devices, 45 comprising a stem, an element formed of insulating material having a central bore, whereby to permit insertion of the same over said stem, a portion of said element having a larger bore than that portion thereof contacting with the stem, said first-named portion 50 having a groove formed therein, terminated by a plurality of parallel disposed and oppositely directed tongues, said tongues being adapted to guide hair being wound on said stem in either direction.

55 3. A winder element for hair waving devices, comprising a stem, a hollowed element of insulating material having a central bore, whereby to permit insertion for reciprocation 60 and rotation of the same over said stem, said element having a notch formed thereon, the terminals of said notch being defined by a plurality of substantially parallel disposed tongues extending oppositely in spaced relationship one with respect to the other, said 65

tongues being adapted to guide and maintain within the notch the hair wound by said element on said stem as the winder element is rotated in either direction.
